UNITED STATES PATENT OFFICE

2,517,446

FOG SUPPRESSING GAS BURNING HEATER
SYSTEM

Frank A. Ryder, Chicago, Theodore Y. Korsgren,
Winnetka, and Arthur R. Collins, Park Ridge,
Ill., assignors to Stewart-Warner Corporation,
Chicago, Ill., a corporation of Virginia

Application November 5, 1945, Serial No. 626,604

2 Claims. (Cl. 158—7)

1

This invention relates generally to heating systems, and more particularly to improved heating systems for small buildings.

It is customary to provide a chimney or stack for carrying away the products of combustion of a furnace or other heater, even in the case of heating systems particularly adapted for use in small buildings. A chimney represents a considerable proportion of the cost of a building. The proportionate cost of a chimney in a small building is especially high, and the elimination of the need for a chimney in such buildings results in a great saving in construction costs. The heating system of the invention provides for the discharge of the products of combustion into the exterior atmosphere through the side wall of the building, thus making it unnecessary to provide a chimney, and yet providing for the positive flow of such products from the heater. With such an arrangement, there is objectionable condensation of moisture contained in the combustion products upon contact with the relatively cold outer air. This is particularly true of gas fired heaters. To prevent the possibility of such condensation, means are provided in the present heating system so that condensation does not occur upon such contact.

It is an object of this invention to provide an improved heating system, particularly adaptable for heating small buildings, which eliminates the need for a chimney.

Another object is to provide an improved heating system particularly adaptable for small buildings in which means are provided for discharging products of combustion through a side wall of the building.

A further object is to provide an improved heating system, particularly adaptable for small buildings, discharging the products of combustion through a side wall of the building, in which means are provided to prevent the formation of a cloud of condensed vapor at the exhaust outlet.

It is also an object of the invention to provide a heating system discharging products of combustion through a side wall of a building to the exterior thereof and having means for diffusing the products of combustion through an air stream for discharge in mixed condition therewith.

Other objects and advantages of the present invention will become apparent from the ensuing description of an embodiment thereof, in the course of which reference is had to the accompanying drawings, in which:

2

Fig. 1 is a central vertical sectional view through the heater, with parts in elevation and parts in fragmentary section;

Fig. 2 is a horizontal cross sectional view taken substantially along the line 2—2 of Fig. 1, with parts in elevation and parts in fragmentary section; and

Fig. 3 is a fragmentary elevational view taken substantially along the line 3—3 of Fig. 2, with parts in fragmentary section.

This invention is in the nature of an improvement on the heating system disclosed in the co-pending application Serial No. 596,130, filed May 28, 1945, by Theodore Y. Korsgren and Frank A. Ryder and now abandoned.

The heater is illustrated as comprising a substantially cylindrical housing 10 suitably secured at its upper edge to a flange 11. The flange is shown as circular in shape and is secured to the flooring 16 by screws not shown. A register 12 covers the opening in the floor and is supported by a horizontal flange portion 14. The register has a plurality of sloping baffles 18, the spaces between the central baffles providing ports for the discharge of heated air as indicated by the upwardly directed arrows in Fig. 1, while the spaces between the outer baffles provide ports for the admission of ventilating air, as indicated by the downwardly directed arrows. Since the upward flow of heated air is at a substantial velocity, the heated air will be forced into the room while cool air will flow along the floor and downwardly between the outer baffles.

Filters 20 may be provided to remove foreign matter from the downwardly moving air. Each filter may comprise a pair of spaced foraminated plates 22 between which a suitable filtering material 24 is disposed. The filters 20 may be supported between an upper apertured rectangular plate 26 and a lower apertured partition plate 28 to cause the entering air to flow through the filters in the directions indicated by the arrows.

The heating unit comprises a casing 30 of generally cylindrical shape having an adapter 32 at the top thereof providing a generally rectangular outlet. A flaring pipe section 34 of rectangular cross section is secured to the adapter 32 and is provided with deflectors 36 at its upper end. The casing 30 has its lower end joined to an inlet extension 38 which has legs 40 resting upon the bottom wall 42 of the housing 10. A heat exchanger 44 is suitably mounted in the casing 30. The heat exchanger is shown as being of the spiral type wherein the products of combustion flow spirally outwardly from a center chamber

46 through a spiral passageway 48 to an exhaust or outlet fitting 50, this fitting extending through the housing 10.

Combustion takes place within a combustion chamber 52 secured to the heat exchanger 44 and communicating directly with the center chamber 46 thereof. In the particular heater shown, domestic gas is used as the fuel and is supplied through a pipe 54. Gas is supplied to a pilot burner 56, projecting into the combustion chamber, through a conduit 58. Gas for normal combustion is supplied to a main burner nozzle 60 through a conduit 62. The flow through the conduits 58 and 62 is controlled by suitable valve mechanisms 64 and 66, respectively, which may be of the solenoid-actuated type well known in the art. A spark plug 68 having its electrode within the combustion chamber 52 may be employed to effect ignition of the pilot flame.

Circulation of ventilating air through the heater is induced by a fan 70 driven by a motor 72 suitably supported from the legs 40. The fan draws cool air downwardly through the housing 10 about the casing 30 and blows it upwardly through the spiral passageway formed by the walls of the exhaust passageway 48 and the casing 30, as indicated by the arrows in Fig. 1.

An thermostat (not shown) may be employed to control the operation of the main burner 60 and fan 70 to maintain a desired temperature in the room or building being heated. A manual control rod 74 may be provided for starting and stopping the operation of the heater as desired, this control rod controlling energization of the spark plug 68 and flow of gas through the pilot flame control valve mechanism 64. As shown in Fig. 1, the rod 74 may actuate both a lever 76 for controlling electric switches in a box 78, and a lever 79 for opening and closing a pushbottom type valve 82 in the valve mechanism 64.

An exhaust pipe 80 is connected by a suitable adapter fitting 83 to the outlet fitting 50, and, as shown in Fig. 2, extends substantially horizontally to a side wall 84 of the building. A discharge conduit 86 jackets the exhaust pipe 80, having one end closed and secured to the exhaust pipe by an adapter 88 adjacent the heater. The other end of the discharge conduit 86 projects beyond the discharge end of the exhaust pipe 80, and extends through the wall 84, so as to vent to the exterior atmosphere. The exhaust pipe 80 and discharge conduit 86 may be held in suitably spaced relation by spacing means (not shown) of any suitable type. By this arrangement, no chimney or vertical flue is required in the building, since the exhaust gases are led through a relatively short conduit from the heater to the open air. The flow of exhaust gases is not hindered by the absence of a vertical passage therefor, so that the efficiency of the heating system is not lowered. At the same time, the construction cost of the building is reduced, and the trouble and expense incident to the cleaning and maintenance of a chimney is avoided. The construction just described, by which the exhaust gases are discharged horizontally through a side wall instead of vertically through the roof, is distinctly advantageous.

A diffuser 90 is connected to the discharge end of the exhaust pipe 80, and may suitably take the form of a perforated cap, although it may be of any other desired construction as, for example, an open tubular member with perforations in the wall thereof. A baffle plate 92 is secured in the conduit 86 between the open end

thereof and the diffuser 90 to cause turbulence and thereby promote better mixing.

An air inlet conduit 94 has one end thereof extending through the wall 84, with the other end connected to a flaring adapter fitting 96 which leads to the housing 98 of a blower 100 driven by motor 102. The latter may be supported from the housing 10 by a suitable bracket 104. A suitable adapter 106 connects the blower housing 98 with two conduits 108 and 110, a portion of the air drawn through the inlet conduit 94 being forced through each of these conduits 108 and 110 by the blower 100. The conduit 108 leads to the combustion chamber 52 to conduct air for combustion to the burner. The products of combustion pass from the burner into the center chamber 46 and through the spiral exhaust passageway 48, outlet fitting 50, and adapter fitting 83 into the exhaust pipe 80.

The conduit 110 leads from the blower to the discharge conduit 86, being connected thereto in any suitable manner adjacent the closed end thereof, as by means of a branch 87 of the conduit 86. A portion of the air drawn through the inlet conduit 94 thus by-passes the heater and flows through the discharge conduit 86 and around the exhaust pipe 80 to vent to the atmosphere. In its passage through the discharge conduit 86, this air, which may conveniently be termed diluent air, mingles with the products of combustion issuing from the exhaust pipe 80 through the diffuser 90, the mixing of the exhaust gases and diluent air being promoted by the restriction provided by the baffle plate 92. The mixture flows past the baffle plate 92 to the atmosphere. The portions of the discharge conduit 86 and the inlet conduit 94 which project through the wall 84 may conveniently be disposed adjacent each other, so that a single opening in the wall may accommodate both conduits. A screen or filter 113 may be provided in the inlet conduit 94 to bar the ingress of foreign bodies. A suitable shield or hood (not shown) may be provided to shield the open ends of the conduits 86 and 94 from rain and the like.

The exhaust gases or products of combustion produced in the burner and passing through the exhaust pipe 80 contain a high proportion of moisture. The exhaust gases are at an elevated temperature, and this elevated temperature combined with the high moisture content results in the gases having a relatively high dew point. If the exhaust gases are discharged directly into the relatively cold outside air, normally present during the operation of a heating system, an objectionable cloud of condensed vapor might form immediately adjacent the outlet and the wall 84 of the building unless the exhaust gases are very hot. In the apparatus described, the addition of diluent air at the diffuser 90 and the provision of baffle plate 92 prevent such cloud formation. The diluent air and exhaust gas mixture has a temperature somewhat lower than that of the exhaust gases, but still considerably higher than the outside atmosphere. The mixture also has a somewhat lower proportion of moisture than the exhaust gases, since the diluent air does not contain as large a proportion of moisture as do the exhaust gases. The relative humidity of the mixture of diluent air and exhaust gases is therefore lower, resulting in a lower dew point for the mixture. When this mixture of lower dew point passes into the outer atmosphere, none or very little vapor condenses, and no vapor cloud is formed.

The cloud preventing effect depends upon the

temperature of the exhaust gases and the quantity and humidity of diluent air. The higher the exhaust gas temperature, and the greater the quantity of air mixed therewith within limits, the better the results obtained. This general statement of the principle involved is subject to limitations imposed by practical considerations, but most satisfactory results are obtained within these limitations by applying the two factors mentioned, that is, the high exhaust gas temperature and the quantity of diluent air, in varying combinations. Increasing the exhaust gas temperature and increasing the quantity of diluent air both tend to decrease the over-all efficiency of the heating system, and it is therefore desirable not to increase the exhaust gas temperature or the diluent air flow rate more than necessary to prevent the clouding effect.

As an example, we have found that with an exhaust gas having a temperature of between 500 degrees and 600 degrees Fahrenheit the addition of about 20 to 30 per cent diluent air is sufficient, if the exhaust pipe is short. Without any diluent air much higher exhaust temperatures would be necessary.

The maintenance of a high temperature in the exhaust gases is assisted by the flow of diluent air about the exhaust pipe, which results in insulating the exhaust pipe against substantial heat loss. Most of the heat lost by the exhaust gases is transferred to the diluent air, which is of advantage since it is not lost to the system inasmuch as the diluent and exhaust air are to be mixed eventually anyway. Therefore, the temperature of the mixed gases at the discharge end of the pipe 80 is only slightly less than they would be at the outlet fitting 50. The diluent air thus serves both to conserve the heat of the exhaust gases until the zone of mixing adjacent the diffuser 90 and baffle plate 92 is reached, and to produce with the exhaust gases a mixture of high temperature and low relative humidity and consequent low dew point, as already explained. In order to get the full benefit of this insulating effect, especially with long thin exhaust pipes, more diluent air should be used than proposed above. For instance, with a pipe fifteen feet long, as much as 200 per cent diluent air can be used to advantage.

Instead of jacketing the exhaust pipe by the discharge conduit 86, the exhaust gases and the diluent air may be conveyed separately to a mixing fitting or chamber and discharged therefrom to the outer atmosphere, if desired. In this case, the diluent air would not jacket the exhaust pipe and provide heat insulation therefor, and accordingly it would be desirable to insulate the exhaust pipe against heat loss.

With exhaust pipes which are relatively short, the mixing of diluent air and exhaust gases may take place at a point quite close to the heater. In such case, the jacketing of the short length exhaust pipe 80 by the discharge conduit 86, or the insulation thereof by other means, would be unnecessary. It appears that the location of the mixing zone relatively close to the outlet to the atmosphere is the important consideration. If this location is relatively remote from the heater,

provision should be made to minimize the heat loss from the exhaust pipe, while if this location is close to the heater as well as to the outlet, the heat loss is so slight as to render unnecessary any insulation of the exhaust pipe.

Having thus described our invention, what we claim as new and desire to secure by Letters Patent is:

1. In a heating system including a gas burner, an exhaust pipe to conduct products of combustion including a high concentration of water vapor from said burner, a fog suppressing system comprising a perforated extension on the discharge end of said pipe for diffusing said products, a conduit surrounding said pipe for substantially its full length and terminating in the outside atmosphere in a venting end beyond said extension, means restricting the interior of said conduit intermediate said extension and said venting end, and means to force air through said conduit about said pipe and extension in the direction of flow of said combustion products, the last said means introducing said air into said conduit adjacent said heater, whereby heat insulation is provided for said pipe and said combustion products and air are intermingled in the vicinity of said extension and restricting means to provide a low dew point mixture for discharge to the atmosphere.
2. In a heating system including means forming a combustion chamber and a gas burner therein, a pipe connected to said combustion chamber for exhausting combustion products having a high concentration of water vapor therein from the combustion chamber, a conduit surrounding said pipe for substantially its full length and terminating in the outside atmosphere to define an annular space between said conduit and said pipe, means to force cold atmospheric air into said annular space adjacent said combustion chamber, and means at the outlet end of said exhaust pipe for mixing air from said conduit with the products of combustion from said exhaust pipe adjacent the termination of said conduit and for exhausting said mixture to the atmosphere.
